UNITED STATES PATENT OFFICE.

FRIEDRICH DEMEL, OF TWICKENHAM, ENGLAND, ASSIGNOR OF ONE-HALF TO RICHARD TINDALL LEIGHTON, OF HOVE, SUSSEX, ENGLAND.

MANUFACTURE OF GOLD LEAF.

Application filed October 29, 1923. Serial No. 671,550.

To all whom it may concern:

Be it known that I, FRIEDRICH DEMEL, a subject of the King of Great Britain, residing at Twickenham, England, have invented 5 certain new and useful Improvements Relating to the Manufacture of Gold Leaf, of which the following is a specification.

In United States Specification No. 198,209 dated 3rd October 1877 is described a process 10 for making gold leaf by electrolytic deposition of gold. In principle the process consists in depositing the metal upon a suitable substance and subsequently removing such substance by heat or solvent. Copper in 15 thin sheets is stated to be a suitable substance; the gold is to be deposited on one side of the sheet which is then to be floated copper side downwards upon a bath of dilutenic acid; the acid dissolves the copper, leaving the gold floating in the form of leaf.

The statement is not sufficient to enable the reader to make gold leaf because it contains no direction as to how the copper sheet is to 25 be gilded.

It is essential that the gilding shall be strictly confined to one face of the base metal, and since the other face has to be dissolved 30 protective varnishes or the like are out of the question or greatly complicate the operation.

By this invention a band or strip of base metal unprotected by varnishes or the like is gilded on one face only by bringing the face which is to be gilded into contact with an 35 electrolytic bath under such conditions that the liquid cannot flow over the edges of the band on to the face which is to remain without gilding.

In the accompanying diagrammatic drawings, Fig. 1 represents a sectional elevation of one form of apparatus suitable for carrying out the invention and Fig. 2 is an 40 end view and Fig. 3 a side view of a modified portion of the apparatus.

In Fig. 1, a silver band *a* which conveniently is not less than 0.0005 inch or more than 0.001 inch, is originally wound up on drum *b* and is unwound therefrom by being wound up on drum *c*. As it leaves the drum 45 *b* it is guided by rollers *d* on to the surface of a bath of gold solution *e* which may suitably contain 4 grams of the double cyanide of gold and potassium per litre. The liquid is prevented by surface tension effects from flow-

ing onto the upper surface of the band. The 55 surface of the band which is in contact with the surface of the liquid is made a cathode by connecting the metallic drum *b* with the negative terminal of a source of electric current. The anode is a carbon plate *f* perforated as at *f'* and immersed in the gold solution at a short distance from the surface of the solution; it is connected with the positive terminal of the source of electric current. Suitable electrical conditions are an 60 E. M. F. of 1.5 volts and a current density of 0.08 ampere per square decimetre of the silver cathode. To ensure uniform maintenance of these conditions and consequent uniform thickness of the deposited film of gold, and 65 also to compensate for the liquid carried from the bath by adhesion to the band, a solution of the double cyanide of gold of the same strength as that of which the bath was made 70 should be allowed to drop continuously into 75 the bath from a vessel such as *g* at the rate found to be necessary. In order to keep the bath as homogeneous as possible in respect of its composition an agitator *h* consisting of a 80 plate of about the same dimensions as the anode *f* may be raised and lowered continuously or intermittently by any suitable mechanism operating on its stem *h'* but not indicated in the drawing; the perforations in the anode permit passage of the solution during 85 the up and down movement of the agitator.

As the gilded silver band leaves the electrolytic bath it passes over a guide roller *i* into a bath of water *k* and then round a roller *k'* submerged in this water. It now leaves the 90 water and is guided by a roller *l* on to a drying drum *m* suitably heated by steam, electric current or otherwise, from which drum it is wound on the drum *c*.

Figs. 2 and 3 illustrate a modified method 95 of carrying out the invention, in which the face of the band which is to remain ungilded is pressed against a drum having an elastic surface, in which the edges of the band are more or less embedded thus preventing flow of liquid onto the said face. The drum *n* consists of a spool-shaped core *o* slipped into a rubber tube *p* which is tied 100 tightly on to the ends of the spool. There is thus formed a pneumatic cushion which can 105 be inflated through a valve *q* of well-known construction. The band *a* is caused by rollers *r* to pass around the greater part of

the drum which revolves in the bath *e*. The of the band to press against the elastic sur- 45
rest of the apparatus resembles that shown face of said drum.

in Fig. 1.

It has been assumed in this description 5
that pure gold leaf is to be made. Commercial gold leaf is strictly speaking an alloy
and when this is required the electrolytic
bath must be so modified in composition that
gold alloyed or mixed with the requisite
10 other metal or metals, such as copper or
silver or both is deposited. The necessary
modifications are known to electro-gilders
and need not be detailed here since they
have nothing to do with the invention.

15 Having thus fully described the nature
of my said invention and the best means I
know for carrying the same into practical
effect, I claim:—

1. Apparatus for electrolytically gilding
20 on one surface a band of base metal, of
which band the other surface is unprotected
by an adhesive coating, comprising an elec-
trolytic bath and means for causing
the band to travel through the bath with
25 one only of its faces in contact with the
electrolyte.

2. Apparatus for electrolytically gilding
30 on one surface a band of base metal, of
which band the other surface is unprotected
by an adhesive coating, comprising an elec-
trolytic bath and means including an elastic
surface against which one face of said band
35 bears, said means and said band being to-
gether movable through said bath.

3. Apparatus for electrolytically gilding
40 on one surface a band of base metal, of
which band the other surface is unprotected
by an adhesive coating, comprising an elec-
trolytic bath, a drum partly immersed
in said bath and free to rotate about its axis,
45 said drum having an elastic surface on its
periphery, means for causing the metal
band to travel through said bath, and means
for causing one face of the immersed portion

4. Apparatus for electrolytically gilding
on one surface a band of base metal, of
which band the other surface is unprotected
by an adhesive coating, comprising an elec-
trolytic bath, a drum partly immersed in
50 said bath and free to rotate about its axis,
said drum having an elastic surface on its
periphery, guide rollers over which the
metal band passes for causing the band to
55 lie partly in the electrolyte with one face
of the portion which is immersed pressed
against the elastic surface of said drum,
and means for imparting longitudinal move-
ment to said bands.

5. Apparatus for electrolytically gilding
on one surface a band of base metal, of
which band the other surface is unprotected
by an adhesive coating, comprising a bath
containing a solution for the electrodeposi-
60 tion of gold, a horizontally disposed drum
partly immersed in said solution and free
to rotate about its axis, said drum having an
elastic surface on its periphery, a roller
from which the metal band is unwound, a
65 roller upon which said band is wound, one
of the said rollers being electrically conduct-
ing, means for connecting the electrically
conducting roller to the negative pole of a
source of electricity, guide rollers over
70 which said band passes and causing said
band to lie partly in the solution with one
face of the immersed portion pressed against
the elastic surface of said drum, an elec-
trode in the solution connected with the
75 positive pole of the source of electricity,
and means for causing the metal band to
travel from the unwinding roller to the
winding roller.

In testimony whereof I have signed my
name to this specification.

FRIEDRICH DEMEL.
